CLAIM

The ornamental design for an expandable power and data center, as shown and described.

DESCRIPTION

FIG. 1 is a perspective view of the embodiment of an expandable power and data center in accordance with my invention;

FIG. 2 is a top plan view of the expandable power and data center in accordance with my invention;

FIG. 3 is a left-side view of the expandable power and data center in accordance with my invention;

FIG. 4 is a front elevation view of the expandable power and data center in accordance with my invention;

FIG. 5 is a right-side view of the expandable power and data center in accordance with my invention;

FIG. 6 is a bottom plan view of the expandable power and data center in accordance with my invention; and,

FIG. 7 is a rear elevation view, rotated 180°, of the expandable power and data center in accordance with my invention.
